UNITED STATES PATENT OFFICE.

FRANK EDWARD ADAMS, OF LOWER BEBINGTON, ENGLAND.

METAL-SCORING MACHINE.

Application filed August 3, 1923. Serial No. 655,424.

To all whom it may concern:

Be it known that I, FRANK EDWARD ADAMS, a subject of the King of England, and residing at Lower Bebington, in the county of Chester, England, have invented Improvements Connected with Metal-Scoring Machines, of which the following is a specification.

This invention has reference to soldered or sealed sheet or thin metal boxes and tins, and means for opening them of the kind, more particularly, wherein a portion of the body, or a strip forming a part of same, is provided with a series of indentations, scorings, or the like in lines of angular disposition, or of an angular and non-angular disposition, and in some cases these indentations, scorings or the like may be in duplicate and parallel, one set on each side of a central line and band of metal to be torn off. The object of such indentations, scorings, or the like is to weaken the metal in the direction of tearing, and in the tearing or severing action to cause the edges of the strip or band to more or less follow predetermined paths.

The invention has for its object and effect to generally provide improvements in connection with such machines by which the work is effected more rapidly, and better, and the machine itself is improved both in durability and in general effectiveness of its operation.

The invention will be described with the aid of the accompanying drawings, which illustrate it.

The invention is illustrated in the annexed drawings, in which Figure 1 shows a sheet of metal, which is to be formed into a can, provided with the scorings or indentations above referred to.

Figure 2 is a side elevation showing part of the machine, Figure 3 is a view showing the opposite side of it, and Figure 4 is an end elevation of the machine.

Figure 5 is a front elevation, Figure 6 a side elevation in section, and Figures 7 and 8 are views showing details, of a modified form of machine, adapted to operate upon a plurality of sheets at the same time.

Referring to the drawings, 1 is the sheet of tin or metal which is to form the body of the box, and 3 is the band of indentations or scorings effected in the machine, consisting of two parallel lines and two sets

of inclined diverging lines within the other two.

A tongue 4 of metal is provided on one edge of the two edges of the sheet which are to be joined together, and will project from the finished can, and by engaging it with a suitable instrument and turning it round, the band within the outer scored lines will tear clean away, so that the upper part of the can is severed from the lower part; and in the act, if either of the tearings of the band comes inward from the upper and lower parallel rings of scorings, the tearing is led back to same by the inclined scorings, and thus faulty tearing is obviated.

The anvil on which the sheets rest and are scored is designated 6, and the sheets are conveyed by an endless chain conveyor 7, with projections 8 on it, to and over the anvil, and such chain being passed over suitable sprocket wheels 9 at the ends of the table 10, along which they are slid, and one of which will be rotated step by step rapidly so as to move the sheet the required distance to receive the blows of the tools at a fresh point for each blow, as hereafter described.

Referring more particularly to Figures 2 to 4, 13 is the frame or head of the machine on which the scoring tools are carried, 18 are the tools, and 19 is the tool holder proper fixed to a slide plate 20, which slides in guides 22 on the head 13, and is vibrated rapidly up and down.

The tool box 19 is secured to the plate 20 by stud bolts 23 which pass through slots in the box, and screw into the plate 20; and the vertical adjustment of the tool box is secured by screws 24 screwing into a crosshead 25 on the plate 20.

The tools 18 are adjustable vertically by vertical screw studs 26 screwing through the top of the box 19, and horizontally by studs 27 screwing through the sides of the box, and pressing on the sides of the tools 18, of which there are four, one for each row of scorings, the lower portion of the tools being supported laterally by inward projections 29 on the inside of the box 19.

The tools are held in the box 19 sideways, that is on the outside, by a clamping plate 35.

Some of the tools may have heads on their tops which touch each other, and they all

come together and touch one another at the bottom, where they score the sheet.

The manner of adjusting and holding the tools enables them to be so placed, that an equal depth of cutting or scoring by all is effected, and without requiring great precision in forming the cutting edges of the tools; and an even and uniform cutting or scoring is effected in a simple and ready manner; and a ready readjustment, and removal and replacing of tools is afforded.

The tools are vibrated rapidly and have a very short stroke, say from 1/16th to 1/8th of an inch, with a rapidity of say 600 to 1500 strokes per minute, whilst the sheet will be moved under the tools step by step at the same rate to produce a continuous scored band 3. This method of operation renders the cost of production low, and commercially possible.

A reduction of the sheet of the usual thickness by the indenting or scorings may be about 4/1000 to 6/1000ths of an inch.

When a sheet has been scored, the slide 20 and tools are inoperative; and they are pressed or held up in their uppermost inoperative positions by any suitable means such as springs, against which the slide and parts carried with it are pressed by the positive downward movement of the slide, the actuation and stopping of which is automatically effected, as hereinafter described.

The primary operating parts of the slide and tools work continuously, and the operation of the tool carriers and slide is effected by a device which is alternately inserted between a driving reciprocating part, and the slide or tool carrier and removed therefrom, so that the ram is actuated or not actuated by the reciprocating part as and when required, and at the required time the indenting or scoring action of the tools is stopped.

The continuously operating mechanism for operating the slide 20 and tool holder 19, consists of a driven shaft 39, which extends through and work in a bearing in the upper part of the head 13, and has on its front end a crank 40, which through a link 41, the lower end of which is on the pin of this crank, operates a lever 42 pivoted on a pin in the frame 13, which operates a reciprocating part 43.

The short arm of the lever 42 imparts to the reciprocating rod or part 43 a small stroke, say about 1/8th of inch; and it may be assumed that the length of the stroke of the reciprocating part 43 is about twice that required by the tools, and that in the upward stroke it moves say 1/16th of an inch above the contact part 45, so that the first portion of the down stroke of the part 43 is inoperative as regards its action on the tool slide 20, and only when it comes on the device 45 is the slide operated, and this is the latter half of the stroke of the part 43.

The lower and upper ends of the link device 41, are separate from and pivotally connected to the intermediate part, so that these parts can move and no strain on the various crank pins and parts takes place.

The bar or part 43, has a circular head 44, fitting and pivoted in the lever 42, and is moved over the part 45 when the sheet is under the tools, but when there is no sheet under the tools, the toe of the part 43 is moved away from the part 45, and the tools are not moved. This is effected by the arm 46, mounted loosely on the shaft 49 and connected to the part 43 by a link 48, being moved back, whereupon a spring 47 connected to 43 70 moves the latter off the block 45. Normally the arm 46 is held in its inward position by a pin 52* on an arm 52 fixed on the shaft 49, which is operated by a crank or arm 50 on shaft 49, a roller 51 which is worked by a cam 53 on the spindle 54, which has fixed on it a ratchet wheel 55, worked by a pawl 56 actuated by an eccentric 57 on the shaft 58, which is worked from the main shaft 39 by spur wheels 59, 60, 59 being half the diameter of 60.

Normally, when the sheet is under the action of the tools, the part 43 will be kept in its operative position over the part 45; but when a sheet is not being scored by the tools, a roller 62 on an arm 63, mounted on a spindle 64, can fall down between the two adjacent ends of the plates on the feeding chain, whereupon an arm 65 on the opposite end of the spindle 64, comes under a projection 66 on the arm 50, (which has been raised by the cam 53) and holds it up, and at the same time the arm 65 will be pulled under the stop 66, and thus the part 43 will be held out of the plane of the part 45, until another sheet passes under the roller 62, and lifts it, and so removes the arm 65 from under the projection 66.

The chain sprocket wheel 9 is operated from the shaft 58 by pawls 30, worked by eccentrics 31 on the shaft 58, and operating two ratchet wheels 32, on a shaft 33 in the frame of the machine. Thus the wheel 9 and the chain conveyor 7 are moved intermittently, and its strokes rapidly following each other, and corresponding with the strokes of the tools on the plates.

It is of course important that the depth of scoring or indenting should be always sufficient, and the different markings should be equal; otherwise the tearing of the band or strip 3 will not of a certainty continue completely round the box formed by the plate, and consequently the severing of the top will be incomplete or faulty; now according to this invention, a method of checking that the required character and quality of scoring is being effected, is furnished by making the sheet itself to show or indicate this. This is accomplished by causing faint

markings to be made on the sheet at one edge by the tools, the markings being scorings of very shallow depth, say about 1/1000ths of an inch deep. This light scoring will be also applied to the edge of the sheet or the tongue 4. To give these faint markings the tools are so set in relation to the anvil on which the sheet is scored, that they will at the end of their stroke, indent 10 the sheet to the degree specified.

In Figure 1 it will be seen that the deeper scorings only commence on the sheet some distance from one edge; and that the faint scorings extend between the deeper ones and 15 the edge of the plate. This is effected by mechanism above described.

Referring now to the modified machine shown in Figures 5 to 8, in this case, the method of operating is to press the sheet 20 on to the tools, which are stationary, and so effect the scorings, instead of pressing the tools on to the sheet as it moves over a stationary anvil or support.

The frame or part 13 on which the stationary tool boxes are mounted, is mounted 25 in a bed 14, over which the chain 7 is passed, the sheets sliding on the inner ledges of the support rails 10.

The tools are carried in their tool boxes 30 19, and adjusted therein similarly as described with reference to Figures 1 to 4, but as stated, the anvils 6 are rapidly vibrated; and in this case they consist each of a bar, either round or other shape in the form of 35 a ram, and supported and guided in a cylinder 16 fixed on to the frame plate 13; and the ram is moved up by the intervention of the insertion device 43, which is moved up and down by the lever 42, similarly as the 40 part 43 in Figures 2 to 4. The lever or arm 42 is rocked about its supporting shaft by a connecting rod or link 41 from the crank shaft 39, and crank 40.

It is important that there be no elasticities or spring in this mechanism, in order 45 that the depth of scoring be permanent, regular and as required; and in order that it may have this quality, the upward movement of the ram 6 is positively limited and stopped when it has moved the required 50 amount, and this is simply and advantageously effected by providing the ram with a collar or enlarged head 17, the upper annular face of which comes in contact with the lower face of the guide cylinder 16, and so determines and assures the length of 55 the stroke with absolute precision, and therefore the depth and quality of the scorings is continuously determined and assured.

In this modified machine, to produce the 60 intermittence of the scoring action of the tools when the sheet passes from them, or before it has left them so as to leave a non-scored or faintly marked portion as above 65 described, the wheel 62 is placed on the

sheet feeding side of the centre of the tools as shown in Figure 5 (also in Figure 1); and the part of the ram 17 which is equivalent to the part 45 in Figures 2 to 4, is of different depths over its face, (or the part 70 of the face which the end of the inserting bar device 43 acts upon), and this bar is pulled slightly away as shown in dotted lines in Figure 8, when it is desired the tools are to score faintly.

75

Instead of the end part 45 of the ram being stepped as shown, it may be curved or inclined, so that the faint scoring may be produced.

The link 48 which is connected with the 80 part 43 and operates it, is actuated through a lever 46 which is pulled by a spring 46* at the required time by a cam 57 on the cam shaft 54; and when the rams are not to receive their full stroke, as when the roller 62 is off the sheet, or no sheet is in, the bar 48 is lowered through the link 68, when its outer end will be away from the head of the lever 6, which normally it will be against when the tools are effecting the 85 full scoring; and thereupon the spring 47 instantly pulls the lever 45 away from the deeper portion of the head 45, so that the full stroke of the part 43 will not be imparted to the ram 6.

90

When this takes place the cam 53 comes 95 into action, and also moves the head of the lever 46 back; and then when the sheet comes over the anvil, and under the roller 62, the link 48 will be pulled up, and the spring 46* will move the lower part of the lever 46 to the cam body, and so the head will press the bar and part 43 into this normal scoring position.

100

In this case, the sheets are supported by 105 one rail 10 at one side, and the ram at the other, while the chain 7 is supported by a longitudinal rail 2.

The chain 7, and sprocket wheel 9, over 110 which it passes at the delivery end, will be operated by palls 30 and eccentrics 31 on a shaft 58, from the main shaft 39 through gearing; and this shaft drives the cam shaft 54 at the required reduced speed through a 115 train of toothed wheels 69, which say gives a reduction of 50 to 1; but this speed may be varied according to requirements.

What is claimed is:—

1. A method of providing a tearable band in metal sheets adapted for the formation of cans or the like, consisting in moving a sheet step by step between a tool and an anvil and subjecting the sheet to rapid blows of the tool to thereby indent the sheet throughout with a series of indentations arranged in alignment to provide a separable section in such sheet.

120

2. A method of providing a tearable band in metal sheets for the formation of cans, consisting in feeding the sheet relative to a 130

tool and an anvil and inducing relative movement between the tool and anvil to successively indent the sheet in a series of aligned indentations to provide a band in the sheet having weakened lines of connection with the sheet throughout its length.

3. A method of providing a tearable band in metal sheets for the formation of cans, consisting in feeding the sheet relative to a tool and an anvil and inducing relative movement between the tool and anvil to successively indent the sheet in a series of aligned indentations, the relative movement between the tool and anvil being variable, whereby to provide a band having lines of separation from the sheet with such lines of varying strengths of connection with the sheet.

4. A method of providing a tearable band in metal sheets adapted for the formation of cans, consisting in feeding the sheet in a step by step movement between a tool and an anvil and inducing relative movement between the tool and anvil at each step movement of the sheet, with such relative movements between the tool and anvil varying at different points of travel of the sheet to thereby form in the sheet a series of successive indentations varying in depth to thereby provide a band which is separable from the sheet along predetermined lines of varying weakness.

5. A machine for providing a tearable band in plates or sheets for cans for containing goods, comprising tools and an anvil, between which the sheets or plates are passed and operated upon by the tools, a contact device operated by the sheets or plates in their travel, means for vibrating the tools or the anvil; and a movable part controlled by the contact device between the vibrating means and the anvil, whereby the scoring or

indenting effect is regulated or controlled; substantially as set forth.

6. In a machine for providing a tearable band in sheets adapted for forming cans, an anvil over which a sheet is progressively fed, a tool box, means for moving the tool box and anvil relative to each other and to the sheet, and a plurality of tools arranged in said tool box to operate on the sheet in the relative movement of the tool box and anvil to form in the sheet a series of indentations defining a tearable band.

7. In a machine for providing a tearable band in sheets adapted for forming cans, an anvil over which a sheet is progressively fed, a tool box, means for moving the tool box and anvil relative to each other and to the sheet, a plurality of tools arranged in said tool box to operate on the sheet in the relative movement of the tool box and anvil to form in the sheet a series of indentations defining a tearable band and means whereby the tools may be independently adjusted in the tool box.

8. A machine for providing a tearable band in sheets, comprising a plurality of indenting tools, an anvil for the sheet, means for inducing a relative movement between the anvil and tools, means for feeding the sheet in a step by step movement relative to the anvil and tools, and means wherein the relative operative movement between the tools and anvil is rigidly limited to avoid elasticity in the action.

In testimony whereof I have signed my name to this specification in the presence of two subscribing witnesses.
